UNITED STATES PATENT OFFICE

HOWARD L. FISCHER, OF ST. PAUL, MINNESOTA, ASSIGNOR TO BROWN & BIGELOW, OF ST. PAUL, MINNESOTA, A CORPORATION OF MINNESOTA

DESIGN FOR A PERPETUAL CALENDAR

Application filed March 22, 1930. Serial No. 34,998. Term of patent 14 years.

To all whom it may concern:

Be it known that I, HOWARD L. FISCHER, a citizen of the United States, residing in St. Paul, in the county of Ramsey and State of Minnesota, have invented a new, original, and ornamental Design for Perpetual Calendars, of which the following is a specification, reference being had to the accompanying drawing, forming a part thereof.

Figure 1 is a perspective view of a perpetual calendar showing my new design.

Figure 2 is an end view of the same showing my new design.

I claim:

The ornamental design for a perpetual calendar as shown.

HOWARD L. FISCHER.
